Japanese Office Action {in Japanese} Dated Mar. 13, 2012 With English Letter of Explanation.

Fish, et al. Lower Extremity Orthoses and Application for Rehabilitation Populations, Foot and Ankle Clinics Website, 2001, 1 Pg.

FIG. 1 is a perspective view of an insole in accordance with my new design;

FIG. 2 is another perspective view thereof;

FIG. 3 is a bottom plan view thereof;

FIG. 4 is a top plan view thereof;

FIG. 5 is a first side elevation view thereof;

FIG. 6 is an opposing second side elevation view thereof;

FIG. 7 is a rear elevation view thereof; and,

FIG. 8 is a front elevation view thereof.

The broken lines in the figures illustrate environmental structure only and form no part of the claimed design.

CLAIM

(57)

The ornamental design for an insole, as shown and described.
